(57) **CLAIM**

The ornamental design for a luminaire, as shown and described.

DESCRIPTION

FIG. 1 is a top perspective view of one embodiment of a luminaire;

FIG. 2 is a bottom perspective view of the luminaire of FIG. 1;

FIG. 3 is a side view of the luminaire of FIG. 1;

FIG. 4 is an opposing side view of the luminaire of FIG. 1;

FIG. 5 is an end view of the luminaire of FIG. 1;

FIG. 6 is an opposing end view of the luminaire of FIG. 1;

FIG. 7 is a top view of the luminaire of FIG. 1;

FIG. 8 is a bottom view of the luminaire of FIG. 1;

FIG. 9 is a top perspective view showing another embodiment of a luminaire;

FIG. 10 is a bottom perspective view of the luminaire of FIG. 9;

FIG. 11 is a side view of the luminaire of FIG. 9;

FIG. 12 is an opposing side view of the luminaire of FIG. 9;

FIG. 13 is an end view of the luminaire of FIG. 9;

FIG. 14 is an opposing end view of the luminaire of FIG. 9;

FIG. 15 is a top view of the luminaire of FIG. 9; and,

FIG. 16 is a bottom view of the luminaire of FIG. 9.

The broken lines shown in the drawings depict portions of

the luminaire that form no part of the claimed design.
